Patented Dec. 7, 1965

203,113

AUXILIARY DENTAL TRAY

Edward O. Shaner, 7424 Wisconsin Ave.,
Bethesda, Md.

Filed Sept. 3, 1964, Ser. No. 81,574

Term of patent 14 years

(Cl. D24—1)

I claim:

The ornamental design for an auxiliary dental tray, as shown.
